FURNACE VALVE OR THE LIKE

Filed May 22, 1951

UNITED STATES PATENT OFFICE

2,668,994

FURNACE VALVE OR THE LIKE

George E. Hansen, Chicago, Ill., assignor to Crane
Co., Chicago, Ill., a corporation of Illinois

Application May 22, 1951, Serial No. 227,667

1 Claim. (Cl. 22—79)

1 This invention relates to a furnace valve or the like construction. More particularly, it is concerned with a metallurgical furnace valve of the duplex type, whereby one of the valves therewithin will allow a certain amount of metal to flow into a chamber for measured release into a mold, and a second valve therewithin allows for the employment and entry of an inert gas, such as helium, to subsequently or preliminarily, as desired, purge the said furnace valve chamber and also the mold connected thereto.

As to the background for this invention, it should be understood that in the pouring of certain metals, such as magnesium in a foundry, for example, problems are involved which differ substantially from the ordinary installations in foundry practice. More explicitly, accuracy in the quantity of melt poured and purging of the equipment before and after use is desirable and often necessary.

Therefore, one of the important objects of this invention is to provide for a valve construction, in which a two-way reciprocally movable valve is employed which can be seated in a measuring casing within the furnace either in a raised or a lowered position. It thus controls the entry of the molten metal into the casing and subsequently controls the discharge therefrom while closing the entry or inlet passage.

Thus, another object is to provide for a valve in which the molten metal is allowed to flow into a casing chamber with a predetermined amount or measured capacity for exactly filling the mold which subsequently forms the desired casting.

Another object is to provide for a furnace valve construction, in which an independent valve working in collaboration with the first-named valve is operable externally for either subsequent or prior purging of the mold and the casing chamber with such inert gas as helium, for example, or the like. Of course, it may not necessarily be a gas, but could be a liquid under certain requirements.

Another object is to provide for a valve construction in which the valve seat may be easily cleaned by mere rotation or partial rotation of the operating handle attached to the stem and disc, thereby aiding in the removal of accumulations, such as foreign matter, slag, or any other sedimental deposits from the valve seat and thereby making it relatively easy to maintain seat tightness.

Another object is to provide for a furnace valve structure in which the valve handles may be easily turned for adjustment in order to suit the installation.

2 Other objects and advantages will become more readily apparent upon proceeding with a reading of the description read in light of the accompanying drawings, in which

5 Fig. 1 is a sectional assembly view of a preferred embodiment of my invention.

Fig. 2 is a fragmentary exterior view in plan of the novel lever actuating mechanism.

Fig. 3 is a fragmentary sectional view taken 10 on the line 3—3 of Fig. 1.

Similar reference numerals refer to similar parts throughout the several views.

Referring now to Fig. 1, let it be assumed that 15 a furnace casing, which is here generally designated 1, constitutes the container for a metallurgical furnace to be used in the pouring of magnesium or the like metals. The lower end portion of the casing 1 is provided with a discharge outlet opening 2 therefrom formed in the cap 3

20 which obviously may or may not be integral with the casing 1. However, as indicated, it is preferably welded at the periphery 4 of the cap 3, as shown. Within an outer recessed portion of the cap 3 and bearing against the walls of the casing 1, a cylindrical casing 5 is provided which is weldably connected, as at 6, thereby to form a casing chamber 7 within which the lower valve seat

25 8 is provided to receive a closure member 9, as illustrated. The furnace 1 includes the metal containing chamber 10. The closure member 9 is preferably of either cylindrical or slight frustoconical form, as illustrated, and is suitably shaped, as at 11, to seat upon the annular portion 8.

At the upper end portion of the closure member 9, a similar seat contact surface 12 is provided for selective engagement as hereinafter described with the underside of the cap 13. The latter cap member encloses the upper part of the chamber 7 preferably by an annular seal weld 14, as shown. As previously indicated, the cap 13 on its inner surface is provided with a suitable annular seat 15 for the seating engagement as above described. It will be noted that in this particular valve construction, the stem 16 is preferably of elongated tubular form, and at its upper end 45 limits is open and is threadedly attached, as at 17, to the hollow pivotal head mounting 18, the tubular stem 16 extending in the usual manner through a conventional centerpiece or guide member generally designated 19 threadedly attached as at 20 and having the stuffing nut 21, the packing gland 22 with the usual packing 23. It will already be apparent that the stem 16 and the closure member 9 are longitudinally movable. 50 As to the manner in which reciprocal move-

ment is obtained, such actuation is effected by means of a track 24 mounted as more clearly shown in Fig. 2 with the vertically extending posts 25 integral with the track and weldably attached, as at 26, to the upper surface of the furnace 1. It will also be noted that the track 24 is substantially semi-circularly extending when viewed in plan and receives the lever 27 which is apertured, as at 28, to be slidably movable arcuately as hereinafter explained on the semi-circular track 24. At the upper end portion of the lever 27, a link pin 29 is employed, being receivable within the bifurcated transverse ear portion 31 of the pivotally mounted lever 32. The central pin 33 serves as the fulcrum point for the latter mentioned lever. It will be clear that, in order to lock the closure member 9 in either the opened or closed position as the tubular stem 16 is actuated, the locking lever 34, bifurcated as at 30, is employed with a thumb nut and bolt 35 frictionally engaging the side surface of the lever 27. The pivotal pin 33 is supported within the fulcrumming member 36 bifurcated as at 40 and having an intermediate space 37 below the pin mounting to receive the pivotal rod 38 which at its end portion is pinned as at 39 to the base member. It is pivotally attached to the bolt 41 by means of the pin 42, the bolt 41 being threadedly attached, as at 43, to the resiliently mounted stem extension member 44, as hereinafter referred to. The pivotal mounting head 18, being hollow, is threadedly attached, as at 45, to the threaded shank of the supporting fulcrumming member 36. The stem extension 44, at its lower end 46, is enlarged to provide an annular shoulder upon which the coil spring 47 is mounted. This arrangement also allows for the threaded attachment as at 48 being made for receiving the inner solid stem 49 which is telescopically mounted and axially movable within the first-named tubular stem 16. The spring 47 thus serves to hold the stem 49 in a lowered axial position. It will also be noted that there is an annular clearance provided between the outside diameter of the stem 49 and the inside wall 51 of the hollow stem 16. At the lowermost end portion of the inner solid stem 49, a seat 52 is provided within the closure member 9, the said lowermost end of the stem 49 being suitably formed at 53 for engagement with the said seat. Below the seat portion 52, a vertical port 54 is provided, having preferably a pair of communicating ports 55 and 56 which discharge into the casing chamber 7 of the measuring container or casing 5 of the metallurgical furnace 1.

As previously indicated, the pivotal head member 18 is threadedly connected to the hollow stem 16 and thereby not only serves as the support for the pivot or fulcrumming member 36, but it also is arranged to receive an inlet conduit or tube 57 having a connection, not shown, with a suitable source of supply of helium gas or the like. From the description given above, it will now be clear that flow thereof downward and into the ports 54, 55, and 56 is controlled by the reciprocating movement of the inner or telescoped stem 49 within the hollow main stem 16. Thus, assuming that it becomes first necessary to cleanse or purge the chamber 7, the lever 38 will be initially actuated, that is, it will be moved upward arcuately thereby to lift the inner stem 49 away from its contact with the seat 52 within the closure member 9. This movement will allow the entering gas to pass downwardly between the annular clearance defined by the stem 49 and the wall 51, past the valve seat 52 and into the

central or vertical port 54 and thence into the transversely extending communicating passages 55 and 56. In this position, the main valve closure member instead of seating at 8, as illustrated, may enter the upper seat 15 on the underside of the cap 13 to render the casing chamber 7 fluid tight and permitting the purging gas to pass outwardly of said chamber into the discharge passage 2, thereby to communicate with the mold (not shown) immediately below and also cleanse the latter, when and if desired.

Let it be assumed further that the casing chamber 7 has been previously cleansed by the flow of the inert gas into said chamber. The main valve is then lowered into the position, as illustrated, by suitable actuation of the lever 32. The valve closure member 9, then seating at 8, allows the port 57 to be opened and in communication with the chamber 10, thus permitting the magnesium or other metal to enter the chamber 7 from the furnace chamber 10. The latter chamber is filled. The lever 32 is again actuated to lift the main stem 16 and bring the closure member 9 into seated position against the seat 15. Evacuation of molten metal from the casing chamber may then take place.

In order to prevent the closure member 9 from dropping by its own weight into the casing chamber, the lever 32 is suitably locked by tightening the thumb screw 35 to engage the vertical lever 27. Thus, the main closure member 9 is held in the raised or upper seated position insofar as the furnace chamber 10 is concerned. It will be apparent, then, that a measured amount of metal is conveniently dischargeable through the outlet 2 from the casing chamber 7 into the mold which has been previously prepared for the entry of such metal by the purge effected through its previous contact with the helium or other suitable gas.

It should, of course, be clear that the levers 27, 32, and 34 being interconnected may by using the track 24 allow for the rotation in an arc of approximately 180°, so as to thereby permit rotation of the closure member, whether in contact either with the seat 8 or the seat 15, marking the lower and upper limits respectively of the chamber 7 may be turned to grind out and thereby remove any accumulations which might otherwise remain upon the respective valve seating surfaces.

The specific manner in which such desirable rotation of the actuating mechanism is obtained may, of course, vary substantially from the structure shown and described.

It should also be clear that the invention is not to be limited to the details of construction and arrangement hereinabove given by way of example, because such construction may be substantially varied to suit the many practical requirements in the foundry industry.

Having now described my invention, what I claim as new and desire to secure by Letters Patent is:

I claim:

In a furnace valve or the like, the combination of a casing within a furnace, the said casing having axially aligned ports, a reciprocally movable ported closure member therefor movable between said casing ports, the said casing ports constituting respectively an inlet and outlet from the said casing, the inlet communicating with the interior of the furnace and the outlet communicating with a mold portion for receiving therefrom molten metal or the like, oppositely disposed valve seats in axial alignment cooperat-

ing with the ports within said casing, one of said seats adjoining said inlet at an upper portion of the casing and the other adjoining said outlet at a lower portion of said casing, the said closure member at end limits of its reciprocal movement alternatively contacting said oppositely disposed valve seats, a plurality of lever means for actuating the said closure member, reciprocally movable closure means within said first-named ported closure member, the said second-named closure means communicating with the ports within the said first-named closure member, the latter ports being in communication with the interior of the said casing, the said second-named closure means predeterminedly interrupting the latter ports, an outer stem for actuating said first-named closure member, an inner stem for actuating said second closure means, the inner stem being substantially contained within the said outer stem, the said outer stem being positioned exteriorly of the furnace and being pivotally connected at an end portion thereof to the said inner stem, the said inner stem being axially movable independently relative to the said outer stem upon actuation of one of said plurality of lever means, the said inner stem at a lower limit of said outer stem

being in communication with at least one of the ports of the said closure member, and inlet fluid supply means on an upper portion of said lever means communicating with the interior of the said outer stem, the fluid flow therefrom at the lower end of the outer stem into the ports of the first-named closure member being controlled by the predetermined axial movement of said inner stem and the second-named closure means relative to the ports of the first-named closure member.

GEORGE E. HANSEN.
